(Cl. D34—15)

To all whom it may concern:

Be it known that I, Theodore Oscar Drescher, a citizen of the United States, residing at Elmont, L. I., in the county of Nassau and State of New York, have invented a new, original, and ornamental Design for A Toy Boat or Similar Article, of which the following is a specification, reference being had to the accompanying drawing, forming part thereof.

In the drawing:
Fig. 1 is a top plan view of a toy boat or similar article, showing my new design;
Fig. 2 is a side elevational view thereof; and
Fig. 3 is a bottom plan view.

I claim:
The ornamental design for a toy boat or similar article, substantially as shown.

THEODORE OSCAR DRESCHER.
